UNITED STATES PATENT OFFICE.

GUSTAF I. JOHNSON, OF MALDEN, MASSACHUSETTS, ASSIGNOR TO AUTOMATIC FLOOR WAXING MACHINE CORPORATION, OF MALDEN, MASSACHUSETTS, A CORPORATION OF MASSACHUSETTS.

DESIGN FOR A COMBINED CASING AND HANDLE SOCKET FOR A FLOOR-TREATING MACHINE.

Application filed August 20, 1928. Serial No. 27,895. Term of patent 14 years.

To all whom it may concern:

Be it known that I, GUSTAF I. JOHNSON, a citizen of the United States, and a resident of Malden, in the county of Middlesex and State of Massachusetts, have invented a new, original, and ornamental Design for a Combined Casing and Handle Socket for a Floor-Treating Machine, of which the following is a specification, reference being had to the accompanying drawings, forming part thereof.

Referring to the drawing,

Fig. 1 is a side elevation of a combined

casing and handle socket for a floor treating machine showing my new design;

Fig. 2 is a front elevation thereof; and
Fig. 3 is a cross-sectional view on the line
3—3 of Fig. 1.

I claim:

The ornamental design for a combined casing and handle socket for a floor treating machine, substantially as shown.

In witness whereof, I hereunto subscribe my name this 18th day of August, A. D. 1928.

GUSTAF I. JOHNSON.
